CRIMINAL APPREHENSION AID

David P. Lindberg, Chicago, Ill.

Application June 6, 1958, Serial No. 740,428

9 Claims. (Cl. 222—145)

This invention relates to a device intended to aid in the detention and apprehension of criminals.

The ordinary citizen is generally defenseless in the presence of one committing a crime upon his or her person. For example, one walking upon a dark street or roadway late at night is particularly prone to attack by criminals bent upon robbery, assault and battery, rape, and other serious crimes. Women and children are particularly defenseless in these circumstances.

The main object of the present invention is to provide a device which will not only constitute a defense weapon usable by a citizen who is being attacked or robbed, but also, will have a function in addition to its defense function, namely, marking the criminal in such a way that apprehension of the criminal after he flees the scene of the crime will be made much easier than is true at the present time.

Another object is to provide a device of the character stated which will be small enough to be carried in the hand, ready for instant use if the occasion demands it.

Another object is to provide a device for defending oneself against criminals and for aiding in the apprehension of criminals, which device will be comparatively inexpensive, will be reusable an indefinite number of times, and will be small and light enough to be carried about in the purse or in one's pocket.

Another object is to provide a device of the character stated that will be provided with a quantity of chemicals, each of which has a particular purpose or function, said chemicals being sprayed in a fully intermixed state so that all the chemicals will be simultaneously in use in the discharge of their intended purposes.

Another object is to provide a device of the character stated wherein the mentioned chemicals will be intermixed responsive to squeezing of the container of the device, and will also be mixed at the same time with a reactor of a chemical nature, to create a pressure adapted to cause a strong spray of jet of the material to be directed forwardly from the nozzle of the device.

Other objects will appear from the following description, the claims appended thereto, and from the annexed drawing, in which like reference characters designate like parts throughout the several views, and wherein:

Figure 1 is a side elevational view of a device according to the present invention, used in defending oneself against and aiding in the apprehension of criminals.

Figure 2 is a longitudinal sectional view therethrough substantially on line 2—2 of Figure 1; and

Figure 3 is a transverse section substantially on line 3—3 of Figure 2.

Referring to the drawing in detail, designated at 10 is a cylindrical container, formed to a constant diameter from end to end thereof, said container being formed of polyethylene or other material of a deformable nature. Such material is often used in the manufacture of so-called "squeeze bottles," such as those used as containers for spray-type deodorants, etc. The plastic material of which the container 10 is formed, thus, normally tends

2

to expand to the position shown in Figure 2. Nevertheless, the container can be gripped medially between its opposite ends, and a squeezing pressure can be exerted thereon. In these circumstances, container 10, intermediate its ends, will be squeezed and contracted in a radial direction, to temporarily reduce the cubic area of the interior of the container. When the squeezing pressure is relaxed, the container tends to expand to its normal, Figure 2 position.

10 Container 10 is integrally formed, at one end thereof, with a rear or outer end wall 12, and also integral with the container is a longitudinal partition 14, which bisects the container longitudinally thereof, the partition 14 coinciding with the longitudinal center line of the container, said partition 14 being disposed wholly in a plane lying diametrically of the container.

Container 10 is also formed with an end wall 16, with which the partition 14 is integral.

Formed upon the rear wall 12, at opposite sides of the partition 14, are inwardly projecting bosses 18, extending about threaded openings 20. Threadedly engaged in the openings 20 are plugs 22, having center bores 24 the inner ends of which are flared as at 26 to provide valve seats.

25 Valve cages 28 are fixedly mounted upon the inner ends of the plugs 22, said valve cages projecting inwardly of the container from the plugs, and being provided at their inner smaller ends with flat, circular abutments 30 centrally apertured to slidably receive the stems 32 of frusto-conical valve elements 34 biased against the seats 26 by compression, coil springs 36 interposed between the valve elements and the abutments 30. Thus, it will be seen that the container, at the outer end thereof, is provided with a pair of transversely spaced inlet check valves, disposed at opposite sides of the partition 14 and opening 30 into chambers A and B defined within the container 10 by the partition.

End wall 16 is provided with inwardly projecting bosses 38 extending about threaded openings 39, in which are threadedly engaged plugs 40 having center bores 42 the outer or forward ends of which are flared to provide valve seats 44. Against these bear conically shaped valve elements 46, the stems of which extend through compression coil springs 50. Springs 50 are held under compression between plugs 40 and abutment washers 52, engaged with stems 48 at the outer ends thereof by pins 53 or the like.

Container 10, at its forward end, is provided with a low, externally threaded neck 54, extending circumferentially of the container and engaged with internal threads provided upon the larger end 55 of a conically shaped, forwardly projecting dispensing head 56, the interior of which defines the mixing chamber C. Head 56 at its forward end is provided with a solid portion constituting a nozzle 58, having an axial, small-diameter bore 60 opening upon the forward extremity of head 56. Bore 60 merges at its inner end into a counterbore 62, threaded to receive a valve plug 64 having an axial bore 65 the forward end of which is flared to provide a conically shaped valve element 66. Element 66 is rigid with a valve stem 67 projecting rearwardly through the bore into the chamber C. A washer is connected to the projecting, rear end of the stem 67, to provide an abutment 68 against which bears the end of a compression, coil spring 70, the forward end of which bears against the plug 64. Thus, the valve within the nozzle 58 constitutes an outlet check valve. The valves in the wall 16 constitute outlet check valves so far as the chambers A, B and are concerned, and inlet check valves 60 so far as the chamber C is concerned.

In use of the device, the chambers A, B would be filled with different liquid substances. Chamber A, for

example, could contain liquid citric acid, intermixed with a fluorescent or luminous liquid. Chamber B could contain a mixture of liquid bicarbonate of soda, together with a dye of a type that would strongly resist efforts to remove the same.

The citric acid has the purpose of acting as a blinding chemical, that is, when sprayed upon the criminal's face, it temporarily blinds the criminal, but does not permanently affect or injure his eyesight. The dye, when sprayed upon the criminal's person and clothes, provides an effective marking of the clothes, so that when the criminal is later apprehended, it becomes clear that there would be no question as to the fact that he was in fact the criminal being sought. So far as the fluorescent liquid is concerned, this serves the same purpose as the dye, in the sense of being a marking liquid. The purpose of the fluorescent liquid is to make the clothes of the criminal luminous, particularly when light is directed thereagainst, to provide a clear outline of the criminal and to make him clearly visible at night, to aid in his apprehension.

The bicarbonate of soda, when mixed with the chemicals in chamber A, reacts to expand. Accordingly, when all the chemicals in chambers A, B are intermixed within chamber C, expansion of the pressure-creating chemical (in this instance bicarbonate of soda) occurs, so that the liquid in chamber C, seeking an outlet, acts upon the valve element 66 to unseat the same. The liquid is thus caused to issue from the nozzle in a thin but very effective jet or stream, which travels a substantial distance against the person of the criminal.

It will be understood that the chemicals mentioned can obviously be varied, and it is mainly important that the chemicals comprise one or more marking chemicals, and, preferably, a disabling chemical such as one that will temporarily blind the criminal. It is also of importance that the chemicals be such that they would include one that will create pressure within chamber C, whenever intermixed with the chemicals from which it is normally separated in the body of the container. For example, in chamber B there could be only one chemical, namely, one that will expand to create pressure when mixed with certain other liquids. In chamber A, said other liquids could be confined. In suspension or otherwise intermixed with the liquids in chamber A there could be the marking dyes, fluorescent particles, etc.

In use of the device, one may carry the same in the hand, ready for use, and of course the device would be so small as to not be normally visible except on close inspection. Assuming that one were attacked by a criminal, the device would be pointed toward the criminal, and the container 10 would be squeezed. This forces the liquids in chambers A, B through the bores 42 in the chamber C, with valve elements 46 being unseated against the restraint of the spring 50.

Within chamber C an immediate chemical reaction takes place, so that heavy pressure is created. Valve elements 46 of course prevent return flow of the chemicals into the chambers A, B. The pressure in chamber C rises to a value such as to overcome the force of the spring 70. The chemicals in chamber C, bearing against the valve element 66, unseat the same and under heavy pressure the chemicals are sprayed through the nozzle against the criminal's person.

When the squeezing pressure is exerted on container 10, valve elements 34 of course remain firmly seated. As soon as the squeezing pressure is relaxed, a partial vacuum will be created in the chambers A, B, which will be replaced by air rushing inwardly through bores 24 and temporarily unseating the inlet check valves 34.

As will be readily apparent, the device has very desirable characteristics, in respect to not only aiding in one's defense against criminals, but also, in marking the criminal so that in the event of his escape, and his later apprehension, he can be readily identified as the

particular person being sought in connection with the commission of a recent crime.

What is claimed is:

1. A device for aiding in the apprehension of criminals, comprising a container formed of a deformable material so as to temporarily reduce its cubic content responsive to a squeezing pressure exerted thereon by a hand grasping the same; a longitudinal partition dividing the container into side-by-side, separate chambers; a dispensing head secured to one end of and projecting forwardly from the container and hollowly formed to provide a mixing chamber in the dispensing head, said dispensing head including a nozzle at its forward end communicating between the mixing chamber and atmosphere; first check valves mounted on the container and arranged to permit flow only from atmosphere into the first named chambers; second check valves mounted on the container and arranged to permit flow only from the first named chambers into the mixing chamber; and a third check valve arranged to permit flow only from the mixing chamber through the nozzle to atmosphere.

2. A device for aiding in the apprehension of criminals comprising a container at least the side wall of which is formed with a material of a deformable nature, so as to temporarily reduce the cubic content of the container responsive to squeezing pressure exerted upon the side wall by a hand grasping the same; a longitudinal partition bisecting the container from end to end thereof to divide the same into side-by-side, separate chambers; a dispensing head detachably connected to one end and projecting forwardly from the container and hollowly formed over substantially its full area to provide a mixing chamber in the dispensing head, said dispensing head including a nozzle at its forward end communicating between the mixing chamber and atmosphere; first check valves mounted on the other end of the container and arranged to permit flow only from atmosphere into the first named chambers; second check valves mounted on said one end of the container and arranged to permit flow only from the first named chambers into the mixing chamber; and a third check valve mounted in the forward end of the dispensing head and arranged to permit flow only from the mixing chamber through the nozzle to atmosphere.

3. A device for aiding in the apprehension of criminals comprising a container at least the side wall of which is formed with a material of a deformable nature, so as to temporarily reduce the cubic content of the container responsive to squeezing pressure exerted upon the side wall by a hand grasping the same; a longitudinal partition bisecting the container from end to end thereof to divide the same into side-by-side, separate chambers; a dispensing head detachably connected to one end and projecting forwardly from the container and hollowly formed over substantially its full area to provide a mixing chamber in the dispensing head, said dispensing head including a nozzle at its forward end communicating between the mixing chamber and atmosphere; first check valves mounted on the other end of the container and arranged to permit flow only from atmosphere into the first named chambers; second check valves mounted on said one end of the container and arranged to permit flow only from the first named chambers into the mixing chamber, said first and second check valves being spring-biased to a normally seated position; and a third check valve mounted in the forward end of the dispensing head and arranged to permit flow only from the mixing chamber through the nozzle to atmosphere, said third check valve being spring-biased to a normally seated position.

4. A device for aiding in the apprehension of criminals comprising a container at least the side wall of which is formed with a material of a deformable nature, so as to temporarily reduce the cubic content of the container responsive to squeezing pressure exerted upon the side

wall by a hand grasping the same; a longitudinal partition bisecting the container from end to end thereof to divide the same into side-by-side, separate chambers; a dispensing head detachably connected to one end and projecting forwardly from the container and hollowly formed over substantially its full area to provide a mixing chamber in the dispensing head, said dispensing head including a nozzle at its forward end communicating between the mixing chamber and atmosphere; first check valves mounted on the other end of the container and arranged to permit flow only from atmosphere into the first named chambers; second check valves mounted on said one end of the container and arranged to permit flow only from the first named chambers into the mixing chamber, said first and second check valves being spring-biased to a normally seated position; and a third check valve mounted in the forward end of the dispensing head and arranged to permit flow only from the mixing chamber through the nozzle to atmosphere, said third check valve being spring-biased to a normally seated position, the spring bias of the valves being selected of a value such as to cause unseating of the valves responsive only to pressure of a predetermined value greater than the value of said spring bias.

5. A device for aiding in the apprehension of criminals comprising a container at least the side wall of which is formed with a material of a deformable nature, so as to temporarily reduce the cubic content of the container responsive to squeezing pressure exerted upon the side wall by a hand grasping the same; a longitudinal partition bisecting the container from end to end thereof to divide the same into side-by-side, separate chambers; a dispensing head detachably connected to one end and projecting forwardly from the container and hollowly formed over substantially its full area to provide a mixing chamber in the dispensing head, said dispensing head including a nozzle at its forward end communicating between the mixing chamber and atmosphere; first check valves mounted on the other end of the container and arranged to permit flow only from atmosphere into the first named chambers; second check valves mounted on said one end of the container and arranged to permit flow only from the first named chambers into the mixing chamber, said first and second check valves being spring-biased to a normally seated position; and a third check valve mounted in the forward end of the dispensing head and arranged to permit flow only from the mixing chamber through the nozzle to atmosphere, said third check valve being spring-biased to a normally seated position, the spring bias of the valves being selected of a value such as to cause unseating of the valves responsive only to pressure of a predetermined value greater than the value of said spring bias, the several valves including axially bored valve plugs having valve seats at one end.

6. A device for aiding in the apprehension of criminals comprising a container at least the side wall of which is formed with a material of a deformable nature, so as to temporarily reduce the cubic content of the container responsive to squeezing pressure exerted upon the side wall by a hand grasping the same; a longitudinal partition bisecting the container from end to end thereof to divide the same into side-by-side, separate chambers; a dispensing head detachably connected to one end and projecting forwardly from the container and hollowly formed over substantially its full area to provide a mixing chamber in the dispensing head, said dispensing head including a nozzle at its forward end communicating between the mixing chamber and atmosphere; first check valves mounted on the other end of the container and arranged to permit flow only from atmosphere into the first named chambers; second check valves mounted on said one end of the container and arranged to permit flow only from the first named chambers into the mixing chamber, said first and second check valves being spring-biased to a normally seated position; and a third check valve mounted

in the forward end of the dispensing head and arranged to permit flow only from the mixing chamber through the nozzle to atmosphere, said third check valve being spring-biased to a normally seated position, the spring bias of the valves being selected of a value such as to cause unseating of the valves responsive only to pressure of a predetermined value greater than the value of said spring bias, the several valves including axially bored valve plugs having valve seats at one end, said valves further including valve elements tapered complementarily to the seats.

7. A device for aiding in the apprehension of criminals comprising a container at least the side wall of which is formed with a material of a deformable nature, so as to temporarily reduce the cubic content of the container responsive to squeezing pressure exerted upon the side wall by a hand grasping the same; a longitudinal partition bisecting the container from end to end thereof to divide the same into side-by-side, separate chambers; a dispensing head detachably connected to one end and projecting forwardly from the container and hollowly formed over substantially its full area to provide a mixing chamber in the dispensing head, said dispensing head including a nozzle at its forward end communicating between the mixing chamber and atmosphere; first check valves mounted on the other end of the container and arranged to permit flow only from atmosphere into the first named chambers; second check valves mounted on said one end of the container and arranged to permit flow only from the first named chambers into the mixing chamber, said first and second check valves being spring-biased to a normally seated position; and a third check valve mounted in the forward end of the dispensing head and arranged to permit flow only from the mixing chamber through the nozzle to atmosphere, said third check valve being spring-biased to a normally seated position, the spring bias of the valves being selected of a value such as to cause unseating of the valves responsive only to pressure of a predetermined value greater than the value of said spring bias, the several valves including axially bored valve plugs having valve seats at one end, said valves further including valve elements tapered complementarily to the seats, the several valves further including stems projecting from the valve elements through the bores of the plugs, the spring bias of the valves being provided by compression, coil springs circumscribed about the stems and bearing at one end against the plugs, the stems having abutments spaced from the plugs against which the other ends of the springs bear.

8. A device for aiding in the apprehension of criminals, comprising a container formed of a deformable material so as to temporarily reduce its cubic content responsive to a squeezing pressure exerted thereon by a hand grasping the same; a longitudinal partition dividing the container into side-by-side, separate chambers; a dispensing head secured to one end of and projecting forwardly from the container and hollowly formed to provide a mixing chamber in the dispensing head, said dispensing head including a nozzle at its forward end communicating between the mixing chamber and atmosphere; first check valves mounted on the container and arranged to permit flow only from atmosphere into the first named chambers; second check valves mounted on the container and arranged to permit flow only from the first named chambers into the mixing chamber; and a third check valve arranged to permit flow only from the mixing chamber through the nozzle to atmosphere, said container being of substantially constant diameter from end to end thereof.

9. A device for aiding in the apprehension of criminals, comprising a container formed of a deformable material so as to temporarily reduce its cubic content responsive to a squeezing pressure exerted thereon by a hand grasping the same; a longitudinal partition dividing the container into side-by-side, separate chambers; a dispensing head secured to one end of and projecting forwardly from

the container, and hollowly formed to provide a mixing chamber in the dispensing head, said dispensing head including a nozzle at its forward end communicating between the mixing chamber and atmosphere; first check valves mounted on the container and arranged to permit flow only from atmosphere into the first named chambers; second check valves mounted on the container and arranged to permit flow only from the first named chambers

bers into the mixing chamber; and a third check valve arranged to permit flow only from the mixing chamber through the nozzle to atmosphere, said dispensing head tapering in a direction forwardly from the container, with the nozzle being disposed at the smaller, forward end of the dispensing head.
